CAP FOR RADIATORS AND THE LIKE

Laurence A. Sweet, Huntington Park, Calif., assignor to Lester K. Franklin, Chicago, Ill.

Application January 29, 1934, Serial No. 708,845

26 Claims. (Cl. 220—24)

This invention relates to caps adapted to be attached over openings in receptacles for making the openings accessible or closing and sealing the openings. Although the invention is capable of embodiment in caps for various types of receptacles as will be apparent from the subjoined specification, the specific embodiment shown and illustrated herein is adapted to a filler cap for radiators and tanks.

The invention is concerned with a cap having a base and a lid hinged to a ring rotatively mounted on the base for angular and axial movement with respect to the base whereby the lid may be locked in closed position on the base and the lid rotatively moved causing the lid and base to be drawn against one another in sealing relation. The present invention has for its objects the provision of a structure which will function as before described. A further object of the invention resides in the provision of locking means for the lid and ring actuated by the rotary or angular movement of the ring with respect to the base.

These objects and other objects which will be apparent from the following description are obtained by the embodiment of my invention illustrated in the accompanying drawings in which:

Fig. 1 is a plan view of a cap with the lid in closed position and partly broken away to more clearly show the construction; Fig. 2 is a plan view of the cap with the lid in open position; Fig. 3 is a section as seen on the plane designated by 3—3 in Fig. 1; Fig. 4 is a section as seen on the plane designated by 4—4 in Fig. 2, a fragment of the lid being shown to make the view more compact; Fig. 5 is a sectional view through Fig. 1 taken at 90° to the view shown in Fig. 3; Fig. 6 is a sectional view through Fig. 2 taken at 90° to that shown in Fig. 4; Fig. 7 is an elevational view of the adaptor base; and Fig. 8 is a cross-sectional view of the ring.

Referring more particularly to the drawings, a cap for the filler tube of a radiator is shown and the specific form of adaptor is that which may be applied to a tube intended for a bayonet type of cap. The present cap is intended to be used in place of the caps which are standard equipment. The adaptor base is denoted by 10. It is recessed on the lower side as indicated by 11 so that it may be mounted over the upper end of a filler tube. An opening 12 is provided in the center of the adaptor. Ears 13 are provided with apertures to receive bolts 14 on which a bayonet plate 15 is secured. The

ears 13, bolts 14 and plate form no part of the present invention and are merely illustrative of a means for securing the cap to a filler tube constructed for a bayonet type of cap. It is obvious that with tubes adapted to receive threaded caps, the recess 11 may have its lateral wall threaded so as to be engageable with the filler tube. A peripheral groove 16 is cut in the adaptor having a bevelled lower portion meeting a shoulder portion at the lower end which serves as a seat for the lid ring. The upper end overhanging wall of groove 16 is formed on diametrically opposite sides of the ring with cam surfaces each comprising a ramp 17 and a dwell 18, as best shown in Fig. 7. At one end of the ramp 17 and on the upper face of the adaptor is an abutment lug 19 and at the far end of the dwell is an abutment lug 20. The upper face of the adaptor between lugs 19 and 20 forms a cam surface corresponding to the cam surface of the groove 16 and therefore having a cam and a dwell. The diametrically opposite side of the adaptor is constructed in a like manner and correspondingly numbered with the suffix *a* added. A channel 21 extends through the upper wall of the groove 16 so as to communicate with the latter.

The lid ring 22 has follower lugs 23 and 23a disposed diametrically opposite to one another and shaped to seat in groove 16. They are of such length that they may be passed through channels 21 and 21a. Immediately above lugs 23 and 23a are apertured projections 24 and 24a which mount follower pins 25 and 25a. The latter ride between abutments 19 and 20 while lugs 23 and 23a ride through a corresponding distance in groove 16. The construction is such that when the ring is rotated or moved angularly with respect to the base it may turn between abutment lugs 19, 20 and 19a, 20a. During its rotative or angular travel, the ring and base will be longitudinally or axially moved in relation to each other and after the followers have passed over the ramps, a limited movement may be obtained during which there is no longitudinal or axial movement. The pins 25 and 25a are removable. To assemble the ring on the adaptor, the pins 25 and 25a are retracted or removed. The ring is placed over the adaptor with lugs 23 and 23a registering with channels 21 and 21a to enable the lugs to be passed to a position alining with groove 16. The ring is then turned to bring channels 21 and 21a out of registration with lugs 23 and 23a and with projections 24 and 24a between abutment 19 and 20 and 19a, 20a. Pins 25 and 25a are then

inserted or projected to their normal positions, thereby locking the ring and adaptor against displacement, the abutments 19 and 19a and the follower pins 25 and 25a preventing lugs 23 and 23a from aligning with channels 21 and 21a and thus preventing disengagement of the ring and adaptor.

On the ring are hinge ears 26 to receive a hinge pin 27. The hinge pin 27 secures the hinge leaf 10 on lid 28. Diametrically opposite the ears 26 is a projection 29 to slidably hold a latch 30 having a downwardly turned follower end. The lid 28 has a keeper recess 31 for entrance therein of the latch. In the upper face of adaptor 10 is a cam groove 32 having an arcuate portion concentric with the adaptor and a slanting portion. The follower portion of the latch rests in the cam groove 32. The cam groove 32 is related to the cam surfaces 17 and 18 so that the slanting portion will act on latch 30 to project the latter prior to the adaptor and lid being drawn together by the rotating movement. The arcuate portion of cam groove 32 is positioned so that the follower of latch 30 is disposed therein while the lugs 23 are in the ramp portions of groove 16. An annular rib 33 is provided on the inner surface of lid 28 to engage a gasket 34 on the adaptor. Thus, when the lid is closed as shown in Fig. 3 the rib 33 will make sealing contact with the gasket.

The cap having been attached to a filler tube is operated in the following manner. Assume the cap is open and in the position shown in Figs. 2 and 4. The lid 28 is first swung downwardly to its closed position and then given a twist. This will cause the ring 22 to rotate or move angularly on its base 19 and the latch 30 to be projected into its keeper thereby locking the lid to the ring. At the last position of the twisting movement, longitudinal or axial movement of the ring in relation to the adaptor occurs so as to move the adaptor against the lid and draw rib 33 into sealing contact with gasket 34. The arcuate portion of cam groove 32 permits this drawing of the lid against the base after locking has occurred. To open the cap, the lid is given a twist in the opposite direction so as to first move the adaptor and lid out of sealing contact and then to unlock the lid enabling it to be raised.

50 What I claim is:

1. A cap for a tank comprising a base having an opening therethrough, a ring rotatively and slidably secured to said base, a lid hinged to said ring to be swung to and from closed position with relation to said opening: cooperative sealing means for said opening carried by the lid and base, said ring and base having a coacting annular cam and follower whereby relative rotation of said ring and base causes longitudinal movement of said ring with relation to said base, and locking means for said lid and base to hold the lid in closed position, said cam and follower enabling said base and lid to be drawn longitudinally together.

65 2. A cap for a tank comprising a base having an opening therethrough, a ring rotatively and slidably secured to said base, a lid hinged to said ring to be swung to and from closed position with relation to said opening: cooperative sealing means for said opening carried by the lid and base, said ring and base having a coacting annular cam groove and follower therein whereby relative rotation of said ring and base causes longitudinal movement of said ring with relation to said base, and locking means for said lid and base

to hold the lid in closed position, said cam groove having a ramp portion and a dwell portion to enable initial limited rotative movement of said ring in locked position of said lid with said base and lid retracted and thereafter to draw said lid and base together.

3. A cap for a tank comprising a base having an opening therethrough, a ring rotatively and slidably secured to said base, a lid hinged to said ring to be swung to and from closed position with relation to said opening: cooperative sealing means for said opening carried by the lid and base, said ring and base having a coacting annular cam and follower whereby relative rotation of said ring and base causes longitudinal movement of said ring with relation to said base, and locking means interposed between said lid and base and operable by rotative movement of said lid to hold the latter in closed position and finally draw said base and lid longitudinally together.

4. A cap for a tank comprising a base having an opening therethrough, a ring rotatively slidably on said base, a lid hinged to said ring to be swung to and from closed position with relation to said opening: cooperative sealing means for said opening carried by the lid and base, said ring and base having a coacting annular cam groove and follower therein whereby relative rotation of said ring and base causes longitudinal movement of said ring with relation to said base, and locking means interposed between said lid and base and operable by rotative movement of said lid to hold the latter in closed position, with said base and lid drawn together, said cam groove having a ramp portion and a dwell portion to enable initial limited rotative movement of said ring in locked position of said lid with said base and lid retracted and finally to draw said lid and base together.

5. A cap for a tank comprising a base having an opening therethrough, a ring rotatively slidably on said base, a lid hinged to said ring to be swung to and from closed position with relation to said opening: said ring and base having a coacting annular cam and follower whereby relative rotation of said ring and base causes longitudinal movement of said ring with relation to said base, said ring and lid having a latch member and a keeper member, one of said members being fixed on said ring and the other member being movable for locking engagement and unlocking disengagement with its companion member, and cam means on said base for actuating said movable member to operate the latter on relative rotation of said ring and base and to effect locking of said lid in closed position with said base and lid drawn together.

6. A cap for a tank comprising a base having an opening therethrough, a ring rotatively slidably on said base, a lid hinged to said ring to be swung to and from closed position with relation to said opening: said ring and base having a coacting annular cam groove and follower therein whereby relative rotation of said ring and base causes longitudinal movement of said ring with relation to said base, said ring and lid having a latch member and a keeper member, one of said members being fixed on said ring and the other member being movable for locking engagement and unlocking disengagement with its companion member, and cam means on said base for actuating said movable member to operate the latter on relative rotation of said ring and base and to effect locking of said lid in closed position with said base and lid drawn together, said cam groove

- having a ramp portion and a dwell portion to enable initial limited rotative movement of said ring in locked position of said lid with said base and lid retracted and finally to draw said lid and base together. 5
7. A cap for a tank comprising a base member having an opening therethrough, a ring member rotatively slidable on said base member, a lid hinged to said ring member to be swung to and from closed position with relation to said opening: cooperative sealing means for said opening carried by the lid and base, said ring having instanding follower lugs, said base having coacting annular cam grooves whereby relative rotation of said ring and base causes longitudinal movement of said ring with relation to said base, said ring having axially extending recesses opening to said grooves to enable lateral insertion of said ring over said base and positioning of said lugs in said grooves, removable follower pins on said ring adjacent said lugs overlying the upper face of said base, said base having abutments limiting rotative travel of said ring beyond registration of said lugs and said recesses, locking means interposed between said lid and base and operable by rotative movement of said lid to hold the latter in closed position, said annular cam grooves each having a ramp portion and a dwell portion to enable initial limited rotative movement of said ring member in locked position of said lid with said lid and base member retracted and finally to draw said lid and base member together. 10
8. A cap for a tank comprising a base having an opening therethrough, a ring rotatively slid- 15 able on said base, a lid hinged to said ring to be swung to and from closed position with relation to said opening: cooperative sealing means for said opening carried by the lid and base, said ring having instanding follower lugs, said base having coacting annular cam grooves whereby relative rotation of said ring and base causes longitudinal movement of said ring with relation to said base, said ring having axially extending recesses opening to said groove to enable lateral insertion of said ring over said base and positioning of said lugs in said grooves, removable follower pins on said ring adjacent said lugs overlying the upper face of said base, said base having abutments limiting rotative travel of said ring beyond registration of said lugs and said recesses, locking means interposed between said lid and base and operable by rotative movement of said lid to hold the latter in closed position, said annular cam grooves each having a ramp portion and a dwell portion to enable initial limited rotative movement of said ring in locked position of said lid with said base and lid retracted and finally to draw said lid and base together. 20
9. A cap for a tank comprising a base having an opening therethrough, a ring rotatively slid- 25 able on said base, a lid hinged to said ring to be swung to and from closed position with relation to said opening: cooperative sealing means for said opening carried by the lid and base, said ring having instanding follower lugs, said base having coacting annular cam grooves whereby relative rotation of said ring and base causes longitudinal movement of said ring with relation to said base, said ring having axially extending recesses opening to said groove to enable lateral insertion of said ring over said base and positioning of said lugs in said grooves, removable follower pins on said ring adjacent said lugs overlying the upper face of said base, said base having abutments limiting rotative travel of said ring beyond registration of said lugs and said recesses, locking means interposed between said lid and base and operable by rotative movement of said lid to hold the latter in closed position, said annular cam grooves each having a ramp portion and a dwell portion to enable initial limited rotative movement of said ring in locked position of said lid with said base and lid retracted and finally to draw said lid and base together. 30
10. A cap for a tank comprising a base having an opening therethrough, a ring rotatively slid- 35 able on said base, a lid hinged to said ring to be swung to and from closed position with relation to said opening: cooperative sealing means for said opening carried by the lid and base, said ring having instanding follower lugs, said base having coacting annular cam grooves whereby relative rotation of said ring and base causes longitudinal movement of said ring with relation to said base, said ring having axially extending recesses opening to said groove to enable lateral insertion of said ring over said base and positioning of said lugs in said grooves, removable follower pins on said ring adjacent said lugs overlying the upper face of said base, said base having abutments limiting rotative travel of said ring beyond registration of said lugs and said recesses, locking means interposed between said lid and base and operable by rotative movement of said lid to hold the latter in closed position, said annular cam grooves each having a ramp portion and a dwell portion to enable initial limited rotative movement of said ring in locked position of said lid with said base and lid retracted and finally to draw said lid and base together. 40
11. A cap for a tank comprising a base having an opening therethrough, a ring rotatively slid- 45 able on said base, a lid hinged to said ring to be swung to and from closed position with relation to said opening: said ring having instanding follower lugs, said base having coacting annular cam grooves whereby relative rotation of said ring and base causes longitudinal movement of said ring with relation to said base, said ring having axially extending recesses opening to said groove to enable lateral insertion of said ring over said base and positioning of said lugs in said grooves, removable follower pins on said ring adjacent said lugs overlying the upper face of said base, said base having abutments limiting rotative travel of said ring beyond registration of said lugs and said recesses, a slidable latch with a follower mounted in said ring, said lid having a keeper for said latch, a latch cam on said base receiving said latch follower, said latch cam having a latch moving portion and a dwell portion enabling rotative movement of said ring and stationary position of said latch with said base and lid drawn together, said annular cam grooves each having a ramp portion and a dwell portion to enable initial limited rotative movement of said ring in locked position of said lid with said base and lid retracted and finally to draw said base and lid together. 50
12. A cap for a tank comprising a base having an opening therethrough, a ring rotatively slid- 55 able on said base, a lid hinged to said ring to be swung to and from closed position with relation to said opening: said ring having instanding follower lugs, said base having coacting annular cam grooves whereby relative rotation of said ring and base causes longitudinal movement of said ring with relation to said base, said ring having axially extending recesses opening to said groove to enable lateral insertion of said ring over said base and positioning of said lugs in said grooves, removable follower pins on said ring adjacent said lugs overlying the upper face of said base, said base having abutments limiting rotative travel of said ring beyond registration of said lugs and said recesses, locking means interposed between said lid and base and operable by rotative movement of said lid to hold the latter in closed position, said annular cam grooves each having a ramp portion and a dwell portion to enable initial limited rotative movement of said ring in locked position of said lid with said base and lid retracted and finally to draw said base and lid together. 60
- 75

- 5 jacent said lugs overlying the upper face of said base, said base having abutments limiting rotative travel of said ring beyond registration of said lugs and said recesses, a slideable latch with a follower mounted in said ring, said lid having a keeper for said latch, a latch cam on said base receiving said latch follower, said latch cam having a latch moving portion and a dwell portion enabling rotative movement of said ring and stationary position of said latch with said base and lid drawn together, said annular cam grooves each having a ramp portion and a dwell portion for said lugs to follow and said upper face having a corresponding ramp portion and dwell portion 10 to enable initial limited rotative movement of said ring in locked position of said lid with said base and lid retracted and finally to draw said lid and base together.

10 13. A closure cap comprising a base having an opening therethrough, means for anchoring the base, a ring mounted around the base for angular and axial movement with respect to the base, a lid hinged to the ring, cooperative sealing means for said opening carried by the lid and base, means 15 operative upon angular movement of the ring for moving the ring axially with respect to the base, and means for securing the lid to the ring.

15 14. A closure cap comprising a base having an opening therethrough, a ring having a lid hinged thereto, the ring and base being mounted for angular and axial movement relative to each other, cooperative sealing means for said opening carried by the lid and base, means for holding the lid in closed position, and means operative 20 upon relative angular movement between the ring and base for moving the ring and base axially with respect to each other.

20 15. A closure cap comprising a base having an opening therethrough, a ring having a lid hinged thereto, the base and ring being mounted for relative angular movement with respect to each other, and locking means comprising a latch bolt movable relative to the lid and ring and means on the lid and ring for receiving the bolt for holding 25 the lid in closed position over said opening, said latch bolt being actuated by the relative angular movement of the ring and base.

25 16. A closure cap comprising a base having an opening therethrough, a ring having a lid hinged thereto, the ring and base being mounted for angular and axial movement with respect to each other, cooperative sealing means for said opening carried by the lid and base, means operative upon 30 relative angular movement between the ring and base for moving the ring and base axially with respect to each other, and locking means for securing the lid to the ring, said locking means comprising a latch bolt movable relative to the lid and ring and actuated by the relative angular movement 35 of the ring and base.

30 17. A closure cap comprising a base having an opening therethrough, a ring having a lid hinged thereto, the ring and base being mounted for angular and axial movement with respect to each other, means for holding the lid in closed position, and cooperative sealing means for said opening carried by the lid and base, the ring and base having coating cam surface and follower means for moving the ring and base axially of each other during at least a portion of their relative angular movement.

35 18. A closure cap comprising a base having an opening therethrough, a ring having a lid hinged thereto, means for anchoring the base, the ring being mounted for angular movement with respect to the base portion, and means operative upon angular movement of the ring for moving the latter axially of the base portion.

40 19. A closure cap comprising a base having an opening therethrough, a ring having a lid hinged thereto, the base and ring being mounted for angular movement with respect to each other, a latch keeper on the lid, an apertured guide on the ring adapted to register with said keeper when the lid is in closed position, a latch bolt reciprocable through said guide into and out of engagement with said keeper when the latter is in registration with the guide, and means associated with said base for reciprocating the latch bolt upon relative angular movement between the ring and base.

45 20. A closure cap comprising a base having an opening therethrough, a ring having a lid hinged thereto, the ring and base being mounted for angular and axial movement with respect to each other, cooperative sealing means for said opening carried by the lid and base, the ring and base having coating cam surface and follower means for moving the ring and base axially of each other during at least a portion of their relative angular movement, a latch keeper on the lid, an apertured guide on the ring adapted to register with said keeper when the lid is in closed position, a latch bolt reciprocable through said guide into and out of engagement with said keeper when the latter is in registration with the guide, and means associated with said base for reciprocating the latch bolt upon relative angular movement between the ring and base.

50 21. A closure cap comprising a base having an opening therethrough, a ring having a lid hinged thereto, the ring and base being mounted for angular and axial movement with respect to each other, a lid hinged to the ring, cooperative sealing means for said opening carried by the lid and base, a cam surface on the upper face of the base having a dwell and a ramp upwardly inclined from the dwell, follower means on the ring adapted to ride in the cam surface, the ramp and follower means causing relative axial movement of the ring and base during their relative angular movement, a cam groove having an arcuate portion and inwardly slanting portion in the upper face of the base, a latch bolt having a projection riding in said groove, the arcuate portion of such groove being so positioned that said projection rides therein when the follower means rides on the ramp, a latch keeper on the lid, and an apertured guide on the ring adapted to register with the keeper when the lid is in closed position, the latch bolt being in alignment with said guide and projectable into and retractable from the keeper when said projection rides in the slanting portion of said cam groove.

55 22. A closure for tanks and the like comprising a ring having a lid hinged thereto, an adaptor base portion within the ring and having an opening therethrough, the ring being mounted for angular and axial movement with respect to the base portion, means for anchoring the base portion, cooperative sealing means on the lid and base portion, means for securing the lid to the ring and comprising a reciprocable latch bolt actuated by the relative angular movement of the ring and base portion, and means operative upon angular movement of the ring for moving the latter axially of the base portion.

60 23. A closure for tanks and the like comprising

a ring having a lid hinged thereto, an adaptor base portion within the ring and having an opening therethrough, the ring being mounted for angular movement around the base portion, means for anchoring the base portion, and means comprising a reciprocable latch bolt actuated by the angular movement of the ring for locking the lid to the ring.

24. A closure for tanks and the like comprising a base having an opening therethrough, a ring having a lid hinged thereto, the ring and base being mounted for relative angular and axial movement with respect to each other, cooperative sealing means carried by the lid and base, means operated during a portion of the relative angular movement of the ring and base for locking the lid to the ring, and means operating during another portion of the relative angular movement of the ring and base for moving the ring and base axially with respect to each other.

25. A closure for tanks and the like comprising a ring having a lid hinged thereto, an adaptor

base portion within the ring and having an opening therethrough, the ring being mounted for angular and axial movement with respect to the base portion, means for anchoring the base portion, cooperative sealing means on the lid and base portion, means operated during a portion of the angular movement of the ring for locking the lid to the ring, and means operating during another portion of the angular movement of the ring for moving the latter axially of the base portion.

26. A closure for tanks and the like comprising a base member and a ring member mounted for angular movement relative to each other, an opening in the base member, a lid hinged to one of said members, and means for locking the lid in closed position over said opening, comprising a latch bolt movable relative to the lid and ring member and actuated by the relative angular movement of said members.

LAURENCE A. SWEET.
